UNITED STATES PATENT OFFICE.

THOMAS M. DEVANNEY, OF CINCINNATI, OHIO, ASSIGNOR TO THE EAGLE COUNTER AND LEATHER COMPANY, OF CINCINNATI, OHIO, A CORPORATION OF OHIO.

FINISHING-MACHINE FOR SHOE-COUNTERS.

1,223,040.

Specification of Letters Patent. Patented Apr. 17, 1917.

Application filed June 4, 1913. Serial No. 771,575.

To all whom it may concern:

Be it known that I, THOMAS M. DEVANNEY, a citizen of the United States of America, and resident of Cincinnati, county of Hamilton, and State of Ohio, have invented certain new and useful Improvements in Finishing-Machines for Shoe-Counters, of which the following is a specification.

This invention relates to finishing machines for shoe counters and particularly to improvements in such machines.

An object of the invention is to produce a counter support plate in which means are provided for decreasing the wear occasioned by the passage of the roller across the plate, during the counter finishing operation.

This and other objects I attain by means of a machine combining the features herein described, and illustrated in the drawings accompanying and forming a part of this application.

In the drawings Figure 1 is a side elevation of a counter finishing machine embodying my invention, with portions shown in section for convenience of illustration.

Fig. 2 is a perspective view of a counter support plate forming a detail of my invention.

Fig. 3 is a section along the line 3—3 of Fig. 2, shown in connection with a fragmental section of the table on which the plate is mounted.

Fig. 4 is a corresponding view along the line 4—4 of Fig. 2.

Fig. 5 is a sectional view taken on the line 5—5 of Fig. 1.

The machine illustrated includes a frame 5, a movable table 6 mounted on the frame, and a finishing or grinding roll 7 journaled on the frame. The table is capable of moving back and forth beneath the roll, for the purpose of moving a shoe counter, carried by it, into engagement with the roll. A counter support plate 8 is mounted on the table

and is provided with a central depression, over which the counter is located, during the grinding or finishing operation. The machine is also provided with the usual clamp 9, which automatically engages the edge of

a counter on the support plate, as the table moves inwardly toward the grinding roll, and which automatically disengages the counter, so that its entire upper surface may be ground by the roll and so that the counter

may be delivered from the machine after it is finished.

A machine having an ordinary counter support plate is objectionable, since the surface of the plate is engaged by the finishing roll 7 during the forward motion of the plate, and consequently, it, as well as the counter, is subjected to the grinding action of the roll. This grinding action on the plate not only tends to, but does, wear it out, and renders it useless in a relatively short time.

I have overcome this difficulty by producing a counter support plate having an elevated or raised counter supporting portion 11, which, in the plate shown in the drawings, extends from the forward edge of the plate rearwardly and parallel to the line of motion of the plate. The edges of the portion 11 are sharply defined, and are preferably vertical, while the outline or perimeter of the elevated portion is substantially the same as that of a counter. The plate is provided with a central opening 12, as is customary in such plates, and the inner edges of the portion 11 are inclined inwardly, so as to form the central depression over which the counter is located during the finishing operation. The forward edge 14, of the plate, is beveled, with the inclined surface of the bevel grading off so that the line between the surface of the portion 11 and the beveled edge is not well defined. In addition to this, the edge 14 is curved, so that it is somewhat crescent shaped, with the horns of the crescent located at the edges of the plate.

A strip 15 of yielding material, such as rubber, is mounted on the table 6, in such a position that a portion of its surface is exposed through the aperture 12 formed in the plate 8, and the plate is adapted to be secured, by any suitable means, into a way, provided on the table 6 for its reception.

The operation of finishing a counter is substantially as follows:

An unfinished counter is placed upon the plate 8 in such a position that its edges register with the vertical edges of the portion 11, as is illustrated in Figs. 3 and 4, in connection with a finished counter 10. As the table 6 moves inwardly, the clamp 9 engages the rear edge of the counter and holds it in place on the portion 11. The roll 7 is preferably so located, with respect to the sur-

face of the plate 8 that, while its grinding face readily engages the surface of the counter supported on the portion 11, it is not capable of contacting with the unraised portion of the plate. With this arrangement the passage of the roll across the plate, during the counter grinding operation, has no detrimental effect whatever upon the plate, since the counter covers and protects the counter-supporting portion 11 and the remaining portion of the plate is out of contact with the roll.

The roll 7 is preferably, but not necessarily, made of some non-abrasive material, such as compressed felt 23, and with the abrasive or grinding surface 24 extending only partially across its cylindrical face, so that the non-abrasive ends 25 and 26 of the roll are exposed. The roll is also preferably mounted so that its bearings 27 and 28 are capable of moving or yielding vertically under the influence of springs 29 and 30, when engaged by the plate, and the beveled edge 14 of the plate is so arranged that its ends will engage the non-abrasive portion of the roll and in this way raise it to the proper grinding, or counter-engaging, position. Under these conditions the abrasive surface of the roll has little opportunity of contacting with the surface of the plate during the forward motion of the table 6.

As the table 6 moves forward, during the grinding operation, it first moves the counter, located on the plate, under the roller 7, and then moves a rack 16, carried by the table, into meshing engagement with a pinion 17, which is mounted on a pressure roller carrying arbor 18. The arbor 18 is journaled in arms 19, which are yieldingly held against a stop 20, on the frame, by means of a spring 21, and the pressure roller mounted on the arbor 18 is adapted to move into engagement with the counter located on the plate, and to hold it in place after the clamp 9 has moved to the releasing position. The pressure roller also aids in delivering the counter through a chute 22, with which the machine is provided, after the counter is ground.

As soon as a counter is finished and delivered from the machine, the table 8 moves back to the position shown in Fig. 1, in which the plate 8 is adapted to receive another counter to be ground. This backward motion of the table is accomplished very rapidly, and consequently, the abrasive action of the roll 7, on the elevated portion 11, has little detrimental effect, even though means are not employed for raising the roll 7 free of the plate during the backward travel of the table.

In accordance with the United States patent statutes, I have illustrated and de-

scribed what I now consider to be the preferred embodiment of my invention, but I desire it to be understood that various changes, modifications and substitutions may be made in the apparatus illustrated without departing from the spirit and scope of my invention as set forth by the appended claims.

What I claim is:

1. A support plate for counter finishing machines, provided with an elevated counter-supporting portion, with an outline substantially similar to the outline of a counter adapted to be supported thereon, and having a curved forward edge, which is inclined at a relatively small angle to the surface of the counter-supporting portion. 75

2. A support plate for counter finishing machines, having a curved and beveled forward edge and being provided with an elevated counter-supporting surface, which terminates in a portion of the beveled edge. 85

3. In a machine of the character described, a reciprocable table, a grinding roller normally below the level of a counter support plate located on the table and capable of yielding vertically, with relation to the table, and having a non-abrasive portion, a counter support plate mounted on the table and having a projection formed thereon for engaging the non-abrasive portion of the roll and for thereby raising the roll to engage a counter located on the plate. 95

4. In a machine of the character described, a reciprocable table, a grinding roll capable of yielding vertically, with relation to the table, and having non-abrasive ends, 100 a plate mounted on the table above the normal level of the roll and having a curved forward edge for engaging the non-abrasive ends of the roll and for raising the roll to a counter-engaging position. 105

5. In a machine of the character described, a yielding grinding roll rotatably mounted on the machine, a reciprocable table movable under said roll, a plate mounted on the table and having an elevated counter-supporting portion formed thereon and located above the normal level of said roll so that the abrasive surface of the roll is capable of engaging only the elevated counter-supporting portion of the plate when the roll is raised by passing the plate under the roll, but is incapable of engaging the unraised portion of the plate. 115

In testimony whereof, I have hereunto subscribed my name this 31st day of May, 120 1913.

THOMAS M. DEVANNEY.
